DENTIFRICE

Earl B. Putt, Haworth, N. J., assignor to Herman Theaman, New York, N. Y.

No Drawing. Application May 23, 1933,
Serial No. 672,467

2 Claims. (Cl. 167—93)

This invention relates to dentifrices, and particularly to the use of certain ingredients therein, which render the dentifrice non-injurious and which confer upon it characteristics which heretofore could not be attained without imposing certain limitations upon the finished product.

In a prior Patent No. 1,565,864, I have replaced the mineral abrasives of the old art by cellulose fiber, thus placing dentifrices on an organic basis. 10 I have followed through the objects of the said patent by this invention, which provides for preparing a dentifrice entirely vegetable in composition so that, for instance, the use of metal compounds may be entirely avoided.

15 I have particular reference to the compounds of the metals of the alkalies. Soap for instance has heretofore been used as an ingredient in dentifrice where a certain foaming quality was to be imparted to the dentifrice. But aside from this last mentioned characteristic soap is primarily a powerful solvent and has other properties which are not always desirable attributes in a dentifrice. Soap is strongly alkaline. On the other hand alkalinity is necessary where soap is used to provide 20 foam, because the foaming quality disappears when a soap containing compound is neutralized or when it is made acidic. It is therefore not possible to make use of the foam producing physical property of soap unless its chemical characteristics are preserved. Whenever foaming is to be provided in a dentifrice by means of alkaline ingredients, the dentifrice must be alkaline and under such conditions it is impossible to provide 25 a foaming, neutral or slightly acid, dentifrice as required by dental authorities in quite many instances.

It is an object of this invention to provide a foaming dentifrice which does not have to be alkaline and which does not have to contain alkaline substances in order to produce foaming.

Aside from attaining freedom in respect to the chemical reaction of a dentifrice I also desire to avoid other disadvantages which accompany the use of soap,—above all, the taste.

40 A novel ingredient for a dentifrice, which I have found to be of great value in order to attain the objects set forth above, is glycol stearate. It forms a milky suspension with water and acts 45 as a detergent. It imparts a soapy taste; but this taste is slight as compared with the characteristic taste of soap. In its flaky, suspended form it aids in removing particles from the teeth in a manner similar to the foam of soap although but 50 little foam is produced. Since it does not dissolve

in water, it provides the bulky base necessary for physically cleansing the teeth.

On the other hand I have discovered that certain alkyl cellulose derivatives, for instance dimethyl cellulose, produce a decided and persistent foam similar to that furnished by soap, and even more lasting than the foam produced by soap. 5

By way of contrast with the case of soap the foaming action caused by dimethyl cellulose in a mixture or compound does in no manner depend on a chemical reaction thereof; in other words it produces a foam when agitated with water in a neutral, acid or alkaline medium. Therefore it is of great use in dentifrices as a foam 10 producing agent, and, since its solution in water resembles that of ordinary gums, it serves as a binder in holding the components of the paste together in a smooth state.

Whereas the glycol stearate and the dimethyl 15 cellulose blend perfectly together when used in neutral or slightly alkaline or acid pastes, glycol stearate should not be used in a strongly acid paste. A formula of a purely vegetable dentifrice which provides a satisfactory foam, and is most 20 effective in cleansing the teeth is the following:

Benzoic acid	—	.15	grams
Glycerin	—	10	grams
Powdered karaya	—	.5	grams
Dimethyl cellulose	—	2	grams
Water	—	90	c. c.
Dry fibre			
(U. S. Patent No. 1,565,864)	—	16	grams
Glycol stearate	—	5	grams
Flavor			
Oil of anise	—	.1	c. c.
Soluble saccharin	—	.1	gram
Menthol	—	.01	gram
Color	—		Eosin 40

In preparing this dentifrice, I proceed as follows: The water is heated to boiling and poured upon the dimethyl cellulose. The mixture is allowed to stand over night and forms a syrupy solution. The glycol stearate is melted at a 45 temperature of 60° to 70° C. The benzoic acid and soluble saccharin are dissolved in the dimethyl cellulose solution.

The powdered karaya is mixed thoroughly with the glycerin. To this is added rapidly the 50 dimethyl cellulose solution previously prepared, and the whole heated to 70° C. This hot solution is now poured into the melted glycol stearate with constant stirring. A heavy white emulsion forms. At this point the fibre is introduced, and 55

the mixture is stirred at intervals until the temperature falls to 40° C.

Then a mixture of the menthol and the oil of anise is mixed thoroughly with the product previously prepared. The addition of the eosin, produces pink color. The paste may then be filled into tubes in the usual manner. The fibre may be used in its original moist state and proper allowance made for the water content.

- 10 In practical tests of this paste, I have found that a one-inch ribbon of the paste, when agitated with 30 c. c. of water, produces 10 to 20 c. c. of foam which is very persistent. Even after 24 hours, such a solution showed a volume of 5 15 c. c. of foam. A commercial sample of a soap containing tooth paste, in a similar test, yielded 20 c. c. of foam, but on standing 24 hours the volume of this foam was reduced to less than 1 c. c.
- 20 For a slightly acid or neutral dentifrice I submit the following example:

	Parts
Glycerin	25.
Powdered karaya	.2
25 Powdered tragacanth	.2
Dimethyl cellulose	2.0
Glycol stearate	3.0
Calcium sulphate	40.0
Tricalcium phosphate	5.0
30 Water	27.0
Saccharin	.05
Benzoic acid	.1
Flavor	.5

- 35 Of course I do not desire to limit the scope of this invention to dentifrices in which soaps or

mineral abrasives are completely eliminated. For instance the glycol stearate may be used without the dimethyl cellulose with a customary amount of gum for a binding agent if a non-foaming dentifrice is desired. If a foaming property is to be imparted to such a compound, either soap or dimethyl cellulose may be used.

The formula for an alkaline dentifrice involving my invention would be the following:

	Parts
Glycerin	25.0
Powdered karaya	.2
Powdered tragacanth	.2
Dimethyl cellulose	2.0
Powdered soap	5.0
Calcium sulphate	40.0
Tricalcium phosphate	5.0
Water	27.0
Saccharin	.05
Benzoic acid	.1
Flavor	.5

While I have described in detail the preferred embodiment of my invention, it is to be understood that the details of procedure, and proportion of ingredients may be widely varied without departing from the spirit of the invention or the scope of the subjoined claims.

What I claim is:

1. A soapless dentifrice comprising dimethyl cellulose as a foam producing ingredient.
2. A dentifrice, in which the solid ingredients substantially are: dimethyl cellulose, glycol stearate and dry fibre.

EARL B. PUTT. 35
